UNITED STATES PATENT OFFICE

118,170

DESIGN FOR A SPACE HEATER

Jean O. Reinecke, Chicago, Ill., assignor to Cole
Hot Blast Mfg. Co., Chicago, Ill.

Application October 5, 1937, Serial No. 71,972

Term of patent 7 years

To whom it may concern:

Be it known that I, Jean O. Reinecke, a citizen of the United States and a resident of the city of Chicago, county of Cook, and State of Illinois, have invented a new, original, and ornamental Design for a Space Heater, of which the following is the specification, and reference being had to the accompanying drawing, forming a part thereof.

Figure 1 is a front perspective view of a space heater on a slightly enlarged scale, embodying my new design.

Figure 2 is a front elevational view thereof; Figure 3 is a side elevational view thereof; and Figure 4 is a front perspective view thereof on a slightly smaller scale with the outer door in opened position.

The three views now numbered Figures 2, 3 and 4, are shown on a slightly smaller scale.

I claim:

The ornamental design for a space heater, as shown.

JEAN O. REINECKE.
